UNITED STATES PATENT OFFICE.

JOHN C. WAHL, OF CHICAGO, ILLINOIS, ASSIGNOR TO REMINGTON ACCOUNTING MACHINE CORPORATION, OF NEW YORK, N. Y., A CORPORATION OF NEW YORK.

CALCULATING MACHINE.

1,418,111.

Specification of Letters Patent. Patented May 30, 1922.

Application filed April 19, 1921. Serial No. 462,622.

To all whom it may concern:

Be it known that I, JOHN C. WAHL, citizen of the United States, and resident of Chicago, in the county of Cook and State of Illinois, have invented certain new and useful Improvements in Calculating Machines, of which the following is a specification.

My invention relates to calculating machines and is embodied in the present instance in a Remington-Wahl combined type-writing and calculating machine of the character known on the market as a "cross footer," and which machine is disclosed in my Patent #1,270,471, dated June 25, 1918; although it should be understood that the invention is not restricted to its embodiment in such machines.

In the construction disclosed in my said patent certain of the "vertical" totalizers 20 which are carried by and adjustable along the carriage are provided with two different sized cams detachably fixed thereto. These cams are adapted during the travel of the carriage to coact with a follower which 25 forms part of the actuator-control or gear shifting mechanism of the cross totalizer. When a cam coacts with the follower the movement of the latter actuates the control mechanism to bring about, at the operation 30 of a numeral key, either subtraction in the cross totalizer, or to disconnect and render the latter inoperative, depending on the character or size of the cam in operation.

In accordance with the present invention 35 I provide on each vertical totalizer, or on each of a number of "dummies" which may be substituted for such totalizers if desired, a cam which is adjustably mounted thereon so that it may be set to coact with a fol- 40 lower such as that referred to above, in the same manner as the two different sized cams disclosed in said patent, and also to obtain a setting of each of said cams for addition. In the construction disclosed in 45 my Patent #1,349,024, dated August 10, 1920, I have embodied two adjustable cams on each vertical totalizer to coact with the control mechanisms of two cross totalizers.

One of the main objects of my present in- 50 vention is to provide an improved adjustable cam mechanism of the character specified. A further object of the invention, generally stated, may be said to be to provide simple, strong and efficient means for effecting an 55 adjustment of a cam on a carrier or totalizer

carried by the carriage, whereby said cam may be readily and accurately set and effectively held in any one of several positions to coact with the follower of a totalizer-actuator control mechanism.

To the above and other ends which will hereinafter appear my invention consists in the features of construction, arrangements of parts and combinations of devices set forth in the following description and more particularly pointed out in the appended claims.

In the accompanying drawings wherein like reference characters indicate corresponding parts in the various views,

Fig. 1 is a detail fragmentary front elevation showing a portion of a Remington-Wahl cross footing machine embodying my invention.

Fig. 2 is an enlarged detail front view 75 with parts broken away and parts in section of a vertical totalizer or "dummy" equipped with an adjustable cam of my invention.

Fig. 3 is a vertical fore-and-aft sectional 80 view of the same taken on the line 3—3 of Fig. 2 and looking in the direction of the arrow at said line.

Fig. 4 is a detail horizontal sectional view 85 of the same taken on the line 4—4 of Fig. 2 and looking in the direction of the arrow at said line.

Fig. 5 is a detail sectional view of the means for attaching the upper portion of the locking plate to the carrier, the section 90 being taken on the line 5—5 of Fig. 2 and looking in the direction of the arrow at said line.

In the drawings I have illustrated only so much of a Remington-Wahl cross foot- 95 ing machine as may be necessary to arrive at an understanding of my invention in its embodiment therein; various of the details of said machine not shown in the accom- 100 panying drawings being well known in the art and fully illustrated in my hereinbefore mentioned Patent #1,270,471.

It will be understood that, in the present instance, the follower 1 carried by a crank arm 2 which is mounted on a rock shaft 105 which is pivoted in the fixed actuator frame 3, may be connected in the usual manner with the actuator-control or gear shifting mechanism of the cross footer (not shown), as is fully illustrated in my said Patent 110

#1,270,471. As is well understood, the follower 1 in its lowermost position sets the control mechanism of the cross footer for "subtraction," whereas the uppermost 5 position of said follower, to which it is moved by a spring, sets said control mechanism for "addition." An intermediate position of said follower, under control of a cam, results in said control 10 mechanism being set to disconnect the actuator of the cross footer.

The member 4 which is, or may be, of the usual construction, and is sometimes referred to as the vertical or main truck 15 or calculator carriage, is connected to travel with the typewriter carriage and travels to the right and to the left therewith. One or more so-called vertical totalizers 5 are detachably mounted on the truck 4, and each 20 is adjustable to different set positions along the truck, where it may be held by a spring-pressed, hand-released latch 6 adapted to engage teeth 7 on the truck.

The adjustable cam of my invention, 25 which coacts with the follower 1 to position the actuator-control or gear shifting mechanism, in some instances is mounted on each vertical totalizer 5. In other instances it is mounted on a so-called "dummy," 30 which may comprise a frame such as the frame of a totalizer 5 but which contains no totalizer mechanism therein and merely constitutes an adjustable carrier for the adjustable cam, and for other parts. Each 35 of these "dummies" is intended to be used in the place of a totalizer 5 when the character of the work is such that no computation is to be entered in the vertical totalizer within the field occupied by the "dummy."

40 With this explanation in mind it will be understood that when I refer herein to a "carrier" for the cam such term is intended to apply to the support on which the cam is adjustably mounted whether such support 45 be a totalizer 5, or a "dummy," or other form of support for the cam.

The frame of the totalizer 5, or "dummy," has its side plates 9 apertured at 10 to receive and have seated therein lugs or reduced end 50 portions 11 of a vertically disposed support or cross plate 12, in order to secure this supporting plate fixedly to the frame.

Riveted to the supporting plate 12, as indicated at 13, and extending forwardly 55 therefrom, are two parallel studs 14 each internally threaded to receive the stem of a headed screw 15. The outer cylindrical surface of each stud 14 forms a pivot bearing for a hub 16 or 17 of an adjusting device 60 or member which in the present instance is in the nature of a lever, as will hereinafter appear. Riveted at 18 to the hub 16 is a sheet metal plate 19 which constitutes a lever arm that extends from its fulcrum or 65 pivot 14 to the left where it is provided near

its end with a rearwardly projecting pin 20. This pin is seated in a horizontally disposed slot 21 near one end of an adjustable sheet metal cam plate 22 arranged parallel with and bearing against the front face of the supporting plate 12. The parallel ends 23 of the plate 22 are received between and coact with the inner faces of the parallel side plates 9 of the frame or carrier, to prevent a longitudinal displacement of the 70 plate 22 on the carrier and to guide the plate in its up and down adjustments thereon to different positions parallel to each other. The plate 22 has a cam edge 75 24 which acts on the follower 1. The cam plate 22 is slotted at 25 to enable the studs 14 to pass therethrough and not interfere with the adjustment of the cam plate on the carrier.

The hub 17 carries a separate adjusting member 26 which corresponds to the member 19, but extends to the right from its fulcrum where it carries a rearwardly projecting pin 27, which is seated in a horizontally disposed slot 28 near the right-hand end of the cam plate. Both of the pivoted adjusting devices 19 and 26 are thus connected by pin and slot connections to the cam plate at different points in the length, or near the ends, of the latter, and are 90 arranged in a plane parallel with the cam plate. A pivotal movement of the adjusting devices in opposite directions is operative therefore to effect a rectilinear up and down adjustment of the cam plate. 100

In order that the pivoted adjusting devices may move in unison, and therefore simultaneously effect corresponding extents of adjustment at opposite ends of the cam, I have provided means whereby a pivotal 105 movement transmitted to one of said devices will cause a corresponding pivotal movement of the other. In the present instance this is brought about by extending each lever-like member 19 and 26 inwardly beyond its fulcrum and hub and providing an interlocking connection between them. Thus, as shown, the member 19 is provided with gear teeth 29 which intermesh with corresponding teeth 30 on the member 26, 115 so that a pivotal movement of the member 19 will cause a corresponding extent of pivotal movement of the member 26, but in the opposite direction, and the pins 20 and 27 will be raised or lowered together 120 and a corresponding adjustment of the cam plate and cam effected at both ends thereof.

In order to provide hand controlled means for effecting an adjustment of the devices 19 and 26, and the cam connected therewith, 125 and for retaining, or positively locking, the same in any of a number of different set positions to which they may be adjusted, I provide a lever-like arm 31 riveted at 32 to the forward end of the hub 16, or other- 130

wise fixedly connected to the hub to turn therewith. The arm 31 may be further fixedly connected to the member 19 by extending the pin 20 forward from the latter at 20^a (Fig. 4) and riveting it at 20^b to the arm 31. The arm 31 extends upward in the rear of a fixed index or locking plate 33 maintained spaced apart from, but secured to the frame of the carrier 5, and situated at the front thereof. This plate may be secured at its lower portion to the carrier by being apertured so as to seat itself on the reduced ends of the studs 14. The head of each screw 15 holds the plate against the shoulder formed on the associated stud where the reduced portion of the stud joins the main body portion thereof, as shown in Fig. 3. The upper position of the plate 33 may be secured to the carrier, as represented in Fig. 5, by two headed screws 34, each of which holds the plate on a reduced portion of a hollow stud or spacing sleeve 35 riveted at its rear end, as at 36, to the casing plate 50 of the carrier. Each screw 34 holds the plate 33 against a shoulder 37 formed by reducing the forward end portion of the stud. The plate 33 has three locking openings or recesses 38 therein arranged in an arc around the pivotal center of the arm 31. A forwardly projecting stud or detent 39 fixed to the arm 31 fits between the side walls of each opening 38 when seated therein, and locks the arm 31 to the plate 33 against turning movement. The arm 31, however, is resilient fore and aft of the machine, or laterally of the direction of its pivotal movement, and may be flexed rearwardly from its locked position to disengage the detent 39 from a locking opening 38. The arm may then be turned to bring the stud opposite another opening 38 and when the arm is released the stud or detent will enter the opening with which it is in register, thus locking the arm 31 and the parts controlled thereby in their newly adjusted positions.

In order to facilitate manipulating the arm 31 I have provided it with a finger piece 40 threaded onto a screw stud 41, the latter being riveted at its rear end to the arm 31. The screw stud 41 and the stem of the finger piece 40 which surrounds it, extend through a curved slot 42 in the plate 33. The ends of the slot 42 coacting with the stem on the finger piece 40, limit the extreme movements of the arm 31 in opposite directions, thus preventing disengagement of the teeth 29 and 30 of the adjusting devices.

I have provided on the front face of the index or locking plate 33, at each opening 38 therein, an index or symbol to aid in properly setting the cam. In the present instance the symbols "S," "D," "A," are arranged from left to right in the order

named, one near each opening 38. When the arm 31 is set and locked in the position shown in Fig. 2, and as indicated by the symbol "S," the cam is adjusted to and locked in its lowermost position, where it will coact with the follower 1 to control the gear shifting mechanism for subtraction. When the arm 31 is adjusted to and locked in the other extreme position at the symbol "A," the cam will be adjusted to and locked in its highest position of adjustment where it will allow the follower 1 to move high enough to set the gear shifting mechanism for addition. When the arm 31 is adjusted to and locked in the intermediate position indicated by the symbol "D," the cam will be adjusted to and maintained in its intermediate position where it acts on the follower 1 lower so as to maintain the actuator for the cross totalizer disconnected. The intermediate and upper positions of the cam edge 24 are indicated in Fig. 2 by broken lines.

It will be seen that in the present construction the manner of mounting the adjustable cam and the parts by which it is adjusted and locked in adjusted position, is such that said cam and said parts cannot drop, or be accidentally detached from the carrier, which detachment might result in the parts in question being misplaced or lost with the consequent annoyance that would result therefrom. The cam plate 12 is guided front and back between the frame plate 12 on the one hand and the parts 19 and 26 on the other, and as hereinbefore pointed out is guided in right and left directions by the frame plates 9.

Various changes may be made without departing from my invention.

What I claim as new and desire to secure by Letters Patent, is;

1. In a calculating machine, the combination of a carriage, a follower forming part of a totalizer-actuator control mechanism, a carrier on said carriage, a cam carried by said carrier and co-operative with said follower, and means on said carrier for adjusting said cam, said means comprising two separate movable adjusting devices co-operative with said cam at different points in the length thereof, and means compelling said devices to move in unison and thus control the movement of the cam to different set positions parallel to each other.
2. In a calculating machine, the combination of a carriage, a follower forming part of a totalizer-actuator control mechanism, a carrier adjustable to different positions along the carriage, a cam carried by said carrier and co-operative with said follower, and means on said carrier for adjusting said cam, said means comprising two separate movable adjusting devices co-operative with said cam, one near each end thereof, means compelling said devices to move in unison.

and thus control the movement of the cam to different set positions parallel to each other, a hand-actuated member for controlling the movement of said devices, and means 5 for locking said hand-actuated member in different set positions.

3. In a calculating machine, the combination of a carriage, a follower forming part of a totalizer-actuator control mechanism, a 10 carrier on said carriage, a cam carried by said carrier and co-operative with said follower, and means on said carrier for adjusting said cam, said means comprising two separate pivoted adjusting devices with interlocking connections between them so that the movement of one causes a corresponding movement of the other of said devices, an operative connection between each of said devices and the cam, and a hand-actuated 15 member connected with one of said devices for controlling its movement.

4. In a calculating machine, the combination of a carriage, a follower forming part of a totalizer-actuator control mechanism, a 20 carrier on the carriage, a cam carried by said carrier and co-operative with said follower, and means on said carrier for adjusting said cam, said means comprising two adjusting devices mounted to turn on separate pivots, interlocking means for causing said devices to turn in unison, a positive connection between each of said devices and said cam, a hand-actuated member connected to one of said pivoted devices to turn 25 it to different set positions, and symbols or indices on said carrier and with which said hand-actuated member is adapted to register to indicate the different positions to which said cam may be adjusted.

40 5. In a calculating machine, the combination of a carriage, a follower forming part of a totalizer-actuator control mechanism, a carrier adjustable to different positions along the carriage, a cam carried by said 45 carrier and co-operative with said follower, and means on said carrier for adjusting said cam, said means comprising two pivoted adjusting devices, intermeshing toothed connections between said devices to cause 50 them to turn in unison in opposite directions, a pin and slot connection between each of said adjusting devices and said cam, and a hand-actuated member for controlling the turning movement of said adjusting devices.

55 6. In a calculating machine, the combination of a carriage, a follower forming part of a totalizer-actuator control mechanism, a carrier on the carriage, a cam carried by said carrier and co-operative with said follower, and means on said carrier for adjusting said cam, said means comprising two pivoted adjusting devices, intermeshing toothed connections between said devices to cause them to turn in unison, a pin and slot 60 connection between each of said adjusting 65

devices and said cam, a hand-actuated member for controlling the turning movement of said adjusting devices, and means for positively locking said hand-actuated member to said carrier in any of the positions to 70 which said member may be moved to determine the different set positions of the cam.

7. In a calculating machine, the combination of a carriage, a follower forming part of a totalizer-actuator control mechanism, a 75 carrier adjustable to different positions along the carriage, a cam carried by said carrier and co-operative with said follower, and means on said carrier adjusting said cam, said means comprising two pivoted adjusting devices connected to turn in unison, pin and slot connections between said adjusting devices and said cam and connecting with the latter at different points in its length, a hand-actuated member for controlling the turning movement of said adjusting devices, a detent carried by said hand-actuated member, an apertured plate fixed to said carrier and in the different apertures in which said detent may be seated to lock said member and the adjusting devices controlled thereby in the different set positions to which they may be adjusted, and a symbol or index near each aperture to indicate each of several different 85 positions to which the cam may be set.

8. In a calculating machine, the combination of a carriage, a follower forming part of a totalizer-actuator control mechanism, a carrier on said carriage, a cam adjustable 100 on said carrier and co-operative with said follower, two adjusting levers operatively connected with said cam at different points in the length of the latter, and hand-controlled means for effecting the adjustment of 105 said levers and including means for compelling them to move in unison.

9. In a calculating machine, the combination of a carriage, a follower forming part of a totalizer-actuator control mechanism, a 110 carrier adjustable to different positions along said carriage, a cam adjustable on said carrier and co-operative with said follower, two levers arranged parallel to the plane of adjustment of said cam and each connected 115 to said cam near one end thereof, hand-controlled means for effecting the adjustment of said levers and including means for compelling them to move in unison, and means by which said levers are retained in different adjusted positions.

10. In a calculating machine, the combination of a carriage, a follower forming part of a totalizer-actuator control mechanism, a carrier adjustable to different positions 125 along said carriage, a cam adjustable on said carrier and co-operative with said follower, two adjusting levers connected to said cam at different points in the length thereof and operatively connected together to turn in 130

unison, and a hand-controlled arm connected to one of said levers for turning it.

11. In a calculating machine, the combination of a carriage, a follower forming part of a totalizer-actuator control mechanism, a carrier on said carriage, a cam adjustable on said carrier and co-operative with said follower, two levers connected to said cam at different points in the length thereof and 10 operatively connected together to turn in unison, a hand-controlled arm connected to one of said levers for turning it, and means for locking said arm in different set positions to which it may be adjusted.

15 12. In a calculating machine, the combination of a carriage, a follower forming part of a totalizer-actuator control mechanism, a carrier adjustable to different positions along said carriage, a cam adjustable on 20 said carrier and co-operative with said follower, a pivoted hand-controlled arm carry-

ing a detent and capable of being flexed laterally of the direction of its pivotal movement to control the engagement and disengagement of the detent, adjusting means 25 controlled by the pivotal movement of said arm and operative to effect a rectilinear adjustment of said cam to different set positions, and an apertured plate fixed to said carrier and in any of the apertures in which 30 said detent is adapted to be seated to lock said arm and the cam controlled thereby in different set positions to which they may be adjusted.

Signed at Chicago, in the county of Cook 35 and State of Illinois, this 15th day of April, A. D. 1921.

JOHN C. WAHL.
